UNITED STATES PATENT OFFICE.

HENRY H. LAMPERT, OF CHICAGO, ILLINOIS.

FORM CLAMP.

Application filed April 16, 1928. Serial No. 270,498.

The main objects of this invention are to provide an improved form of clamp adapted for attachment to a tie element; to provide a clamp which is adapted to be rigidly secured to one end of a tie element and to be adjustable with respect to the other end thereof; to provide an improved form of bearing member on which an adjusting tool may be fulcrumed in pulling said other end 10 of the tie relative to the clamp; and to provide a clamp of this kind which may be stamped out of sheet metal and which is particularly adapted for use as a form clamp in the construction of concrete beams, girders, 15 columns and the like.

Illustrative embodiments of this invention are shown in the accompanying drawing, wherein:

Figure 1 is a perspective of a clamp showing also parts of a tie band.

Fig. 2 is a fragmentary transverse section of a structural shape having supported thereon a clamp attached to one end of a tie band, an adjusting tool being shown in position 25 to pull the other end of the tie band relative to the clamp.

Fig. 3 is a perspective of a modified form of clamp showing the bearing for the tool located at one end of the clamp.

Fig. 4 is a longitudinal section taken on the line 4—4 of Fig. 3, but showing the tie band kinked by the bridge portion.

The improved clamps herein shown are adapted for use in connection with a large 35 number of different types of concrete molds. In the construction shown, the clamp is used for securing a flexible tie element to a structural shape, such as an I-beam 1.

The tie element may consist of a round 40 wire or a flat metal band 2, the size of which depends upon the kind of mold to which the clamps are applied.

In the forms shown the improved clamp 45 comprises a supporting member, preferably a sheet metal stamping, having fastening means for attachment to the ends of the tie band and a bearing part against which an adjusting tool 3 may be fulcrumed. In the form shown in Figs. 1 and 2, the bearing part is 50 located between the ends of the clamp and in the form shown in Figs. 3 and 4, it is located at one end of the clamp.

In the embodiment illustrated in Figs. 1 and 2, the clamp comprises a supporting plate 4 having formed adjacent one end

thereof a pair of recesses 5 and an intermediate bar 6 arranged to permit one end of the tie band to be looped around the bar 6 and doubled back upon itself, so as to be frictionally secured to the clamp.

Adjacent the other end of the clamp, a portion of the plate 4 is struck out therefrom to provide a recess 7 and an overlying bridge portion 8. The bridge 8 is spaced from the plane of the plate 4, to provide a passageway 60 for the tie element.

The bridge portion 8 is bendable and, when struck by a hammer or similar tool, it is adapted to kink the tie element by forcing a portion thereof into the recess 7, so as to 70 secure this end of the tie element to the clamp after it has been adjusted by the tool 3.

Struck out from the plate 4, between the recesses 5 and the recess 7, is a lug 9 disposed substantially normal to the plate 4 to provide a bearing for the tool 3.

The tool 3 comprises a shank which provides a handle and a head 10 on which is pivotally mounted a U-shaped locking jaw 11, which straddles the head 10 and which is pivotally secured thereto by a pin 12. The parts are arranged so that, when the jaw 11 is swung to an angular position relative to the handle, an opening is provided for receiving the tie element so as to permit the tool to grip the 85 portion of the tie projecting beyond the bridge portion 8.

In the form shown in Figs. 3 and 4, the clamp comprises a sheet metal plate 13 having recesses 14 and an intermediate bar 15 spaced from one end thereof to permit attachment 90 of the clamp to one end of the tie band.

Formed adjacent the other end of the plate 13 is a recess 16 and an overlying bridge portion 17 to permit attachment of the clamp to 95 the other end of the tie.

The end of the plate 13, adjacent the recesses 14, is bent upwardly to provide a bearing flange 18 for the tool 3.

In operation, one end of the tie band is 100 looped around the transverse bar 6 or 15 and the tie is then looped around the structural shape, or around the sections of the mold, and inserted through the bridge portion at the other end of the clamp.

The tool 3 is then applied to the projecting 105 end of the tie band and fulcrumed on the bearing member 9 or 18 to pull the tie relative to the clamp. After the tie has been properly adjusted, the bridge portion is forced 110

downwardly for kinking the band, and the tool 3 may then be removed for use on other molds.

Although but one specific embodiment of 5 this invention has been herein shown and described, it will be understood that certain details of the construction shown may be altered or omitted without departing from the spirit of this invention as defined by the following claims.

I claim:

1. A device of the class described comprising a flexible tie element, a sheet metal support mounted on one end of said tie and having 15 a guideway for slidably receiving the other end of said tie, a bearing part struck out from said support, and a detachable tool arranged to grip said other end of said tie and to be fulcrumed on said bearing part for pulling 20 said tie relative to said support.

2. The combination with a flexible tie element, of a form clamp comprising a support,

means for securing both ends of the tie to said support, and a bearing part formed on said support to permit a tie adjusting tool to 25 be fulcrumed thereon, said bearing part being located to one side of the plane of said support for spacing one extremity of said tie from said support.

3. A form clamp comprising a sheet metal 30 plate, and means on said plate for securing both ends of a tie element thereto, a portion of said plate being bent transversely to said plate to provide a bearing part for a separate 35 tie adjusting tool.

4. A form clamp comprising a sheet metal plate having means thereon for attachment to both ends of a tie element, a portion of said plate being bent substantially normal to said plate to provide a bearing part for a separate 40 tie adjusting tool.

Signed at Chicago this 13th day of April, 1928.

HENRY H. LAMPERT.
